William H. Fulton, Inventor

By his Attorney

Thomas Howe

UNITED STATES PATENT OFFICE.

WILLIAM H. FULTON, OF IRVINGTON, NEW JERSEY, ASSIGNOR TO TITEFLEX METAL HOSE CORPORATION, A CORPORATION OF NEW YORK.

TUBE.

1,348,793.

Specification of Letters Patent.

Patented Aug. 3, 1920.

Application filed May 15, 1917. Serial No. 168,653.

To all whom it may concern:

Be it known that I, WILLIAM H. FULTON, a citizen of the United States, residing at Irvington, Union county, New Jersey, have invented new and useful Improvements in Tubes, of which the following is a specification.

This invention relates to tubes formed from a helically wound strip.

10 The main object of the invention is to provide a tube of the character described which shall be of simple construction and require small expense to manufacture, but which shall be strong, reliable and sufficiently tight 15 for many purposes, for instance muffler tubes.

Other and ancillary objects of the invention will appear hereinafter.

In the accompanying drawings, which 20 illustrate the invention,—

Figure 1 is a perspective view of the initial flat ribbon or strip from which the tube is formed;

25 Fig. 2 is a perspective view of the strip after having been formed to have a cross section so that it is suitable for winding into the tube, and

Fig. 3 is a side elevation of the tube, partially in section;

30 Fig. 4 is a fragment showing in section a seam or joint having packing.

Referring to the drawings, a strip 1, of brass, steel or other material of flat, ribbon-like form as shown in Fig. 1, may have its 35 section shaped in any suitable manner into the form as shown in Fig. 2 wherein the strip has a longitudinal center groove 2. Upon one side of the groove 2, is a groove 3 extending longitudinally of the strip, while 40 upon the other side of the groove 2, is a longitudinally extending portion comprising the parts 4 and 5 formed into zigzag relation.

The strip of Fig. 2 may be coiled into a helix as by winding on a mandrel to form 45 a tube as shown in Fig. 3. The zigzag portion adjacent the edge of one convolution is entered within the groove 3 at the adjacent edge of a contiguous convolution, so as to secure the edges of the convolutions together.

50 The extreme outer edge of the zigzag portion bears against the bottom of the groove 3 and the grooved walls being pressed down upon the zigzag portion, the spring of the metal in the latter forces the outer edge 55 against the grooved walls so that a joint

which is tight for many purposes, is secured. It may further be observed that in the structure shown, the different element of 4 and 5 of the zigzag portion, extend from one side of the groove 3 to the other, so that the convolution edges are held from relative movement longitudinally of the tube.

If desired, a packing strip indicated in section at 6 in Fig. 4, may be wound within the groove 3 between its bottom and the edge 65 of the zigzag shaped portion. This will enhance the tightness of the tube where it is required.

While one manner of forming the tube has been stated, it might be formed by other 70 methods.

While the invention has been illustrated in what is considered its best application, it may have other embodiments without departing from its spirit and is not therefore 75 limited to the structure shown in the drawings, the appended claims pointing out the invention, in accordance with the patent statutes.

What I claim is—

1. A tube comprising a helically disposed strip having a longitudinal groove adjacent one edge and a longitudinally extending portion of zigzag section adjacent the other edge, the said portion of zigzag section being 85 within the said groove and having its relatively reflexed portions overlying each other radially of the tube.

2. A tube comprising a helically disposed strip having a central longitudinal groove; 90 a longitudinal groove upon one side of the aforesaid groove and a longitudinally extending portion of zigzag section upon the other side of the central longitudinal groove, the said portion of zigzag section being within the groove upon the other side of the said central groove and having its relatively reflexed portions overlying each other radially of the tube.

3. A tube comprising a helically disposed strip having a longitudinal groove adjacent one edge and a longitudinally extending portion of zigzag section adjacent the other edge, the said portion of zigzag section being within said groove and having its outer edge 100 pressing against the inner wall of the groove by the spring of the metal in the zigzag portion.

4. A tube comprising a helically disposed strip having a longitudinal groove adjacent 110

one edge and a longitudinally extending portion of zigzag section adjacent the other edge, the said portion of zigzag section being within the said groove and having its relatively reflexed portions overlying each other radially of the tube; and a packing between said portion and the walls of said groove.

5. A tube comprising a helically disposed strip having a longitudinal groove adjacent

one edge and a longitudinally extending portion of zigzag section adjacent the other edge, the said portion of zigzag section being within said groove and the elements of the said zigzag each extending from one wall of said groove to another.

In testimony whereof I have signed this specification this 14th day of May, 1917.

WILLIAM H. FULTON.
